BUOYANT MARKER FOR AERIAL TOW TARGET

Francis Vintschger, Morristown, N.J., assignor, by mesne assignments, to the United States of America as represented by the Secretary of the Navy

Application July 29, 1957, Serial No. 674,990

10

11 Claims. (Cl. 9—9)

The present invention relates to a buoyant marker and more particularly to a marker for an aerial tow target, the marker comprising a casing containing a normally collapsed inflatable elastic bag and a gas cartridge with means for releasing the gas and inflating the bag in response to impact of the marker with the surface of a body of water.

In training gunners to become proficient in the use of their arms, be they airborne or ground-based, one of the practices is to connect an aerial target to an aircraft by a long length of cable so it may be towed thereby through the air and furnish a target for the gunners. Such target practice is usually carried out over a body of water, which makes for easier policing of the practice area and more rapid retrieving of the target for evaluation and further use. It is to be understood, of course, that at the completion of the practice the target is cut loose and falls into the water from which it is retrieved by a surface craft standing by at a safe distance. Therefore, if means are not provided for keeping the fallen target afloat, or otherwise marking its location, it may become lost. The target is commonly in the form of a sleeve or banner, the latter having a weighted bar to dispose it horizontal or vertical during towing, as desired.

Various means have been proposed for identifying the location of the fallen targets in water. For example, floatation pockets have been built into sleeve targets but it has been found that after ten minutes or so in the water, the target tends to sink to a depth of one and one-half to two feet, making difficult its location from the surface craft and necessitating the tow aircraft to circle the area and guide the surface craft thereto or requiring a helicopter to come out and pick up the target. Other devices include the provision of a buoy associated with the tow cable which had the disadvantage of introducing a greater drag or load on the towing aircraft.

One of the important objects of the present invention is the provision of a marker the components of which are housed in a container small in size yet when the marker has been operated a position indicator is produced of much greater size and therefore easier identification.

Another object is to provide a marker containing a normally collapsed inflatable element, which in the collapsed condition thereof takes up a small amount of space within the marker container but is adapted to be forced therefrom and expanded to an object identifiable at a considerable distance.

A further object of the invention is the provision of a marker means which comprises an inflatable element, a source of fluid under pressure for inflating the element, and means responsive to impact for releasing the fluid and inflating the element, all compactly contained in a tube.

The exact nature of this invention as well as other objects and advantages thereof will be readily apparent from consideration of the following specification relating to the annexed drawing in which:

Fig. 1 is a pictorial view of the marker of this invention shown attached to a leader cable;

Fig. 2 is an elevational side view of the marker, partly in section, and with parts thereof broken away, the marker being shown in the unarmed or safe condition;

Fig. 3 is a fragmentary sectional view of a portion of Fig. 1 but showing the marker actuating mechanism in the armed condition thereof;

Fig. 4 is a view similar to Fig. 3 with the actuating mechanism shown in the actuated position thereof;

Fig. 5 is a side view in elevation of the main body;

Fig. 6 is a sectional view in plan taken along line 6—6 of Fig. 3 on a larger scale; and

Fig. 7 is a sectional view on line 7—7 of Fig. 5.

Referring now to the drawing, wherein like reference characters designate like or corresponding parts throughout the several views, there is shown in Fig. 1 a marker of the present invention generally designated by reference numeral 11. The marker comprises an elongated tubular container or casing 12, such as a tube or the like, and fixed to the exterior thereof, at longitudinally spaced points thereon, is a pair of lugs 13, each lug having associated therewith a clamp plate 14 secured thereto by bolt screws 15. If desired, each lug and plate may be provided with a groove 16 adapted to receive a leader cable 17, or the like, the ends of which are adapted to be secured by swivel connectors 18, 19 to the tow cable of the aircraft and the tow target respectively.

Turning now to Fig. 2, mounted within tubular casing 12 is a cylindrical housing or tube 21 having an annular groove or channel 22 in the exterior thereof member and into which a pair of screws 23 passing through the casing extend, the external diameter of the housing being substantially equal to the internal diameter of the casing. Secured to the lower end of the housing 21 is a connector or coupling in the form of a tubular member 24 provided with an upstanding circular flange 25 at the upper end thereof and an annular flange 26 normal thereto. The external diameter of the upstanding flange 25 is such as to fit snugly within the cylindrical housing with the annular flange 26 abutting the lower end thereof (as viewed in Fig. 2), suitable fastening means such as set screws 27, or the like, passing through the lower end of the housing for securing it to the flange portion of the tubular connector 24.

The ends of the tubular container or casing 12 constitute a pair of wells 28, 29, the latter of which houses or contains a floatation member in the form of an inflatable elastic element 31, such as a balloon, bag, or the like, which is normally collapsed and suitably rolled to fit within well 29. The inflatable element is provided with the usual mouth portion 32 which receives the tubular connector 24 and is secured thereto in sealed relation by suitable means such as circular clamp means 33, or the like, and cement. The inflatable element in the rolled condition thereof fits snugly within the well 29 to retain the element therein under ordinary conditions. For protecting and further retaining the floatation bag within its well, there is provided a cap 34 which fits within the end of the tubular container 12 and is held therein with sufficient friction to retain the rolled bag there within, the cap being adapted to be forced out by inflation and expansion of the bag as will hereinafter appear. A cover 35 may be provided to protect cap 34 during handling and storage.

Disposed within well 28 of casing 12 is a main body assembly 36 which comprises an actuator assembly 37, a main body 38 supporting the actuator assembly, and a container or cartridge 39 having fluid under pressure sealed therein. The main body 38 is formed with a base 41 and walls 42 defining a cup-like cavity, the walls of the cavity being provided with circumferentially spaced longitudinal slots 43 therein extending from the base through the outer edge of the cavity walls.

For mounting the main body assembly in the tubular container 12, there is provided a support platform 44 in the form of a disc-like member, the outer periphery of which has portions thereof notched to provide a plurality of circumferentially spaced radially directed legs 45, said legs being adapted to be disposed in slots 43 of the main body and to be secured to the tubular container by means of screws 46, best understood by referring to Figs. 2, 4 and 6. Each of the legs 45 is provided with a post 47 which extends coextensively with the major portion of the slot 43 in which it is disposed. Each post has coiled thereabout a compression spring 48 which reacts at one end thereof against said support platform and at the other end thereof against an annular retaining member 49 secured to the cavity walls 42 by screws 51, and bridging the gaps formed by the slots 43 therein. The retaining member is also of sufficient lateral extent to provide an internal retaining flange 52 for reasons hereinafter appearing.

Disposed within the cup-like cavity of the main body 38 is a hub member or element 53 forming part of the actuator assembly 37, the hub member having an annular plate-like portion 54, the outer edge of which is adapted to be engaged by the retaining flange 52. The hub member is also provided with a vane support post 55, which projects from one side of plate-like portion 54 centrally thereof, and with a cylindrical wall portion 56 projecting from the other side of the plate-like portion and defining a chamber 57 therewithin. The vane support post 55 has a set of vanes 58 secured thereto.

Centrally of the chamber 57, there is formed in the plate-like portion 54 a tapered socket 59 with a rounded bottom which receives the rounded end of a thrust-transmitting element, such as a rod or a bar 61, the other end thereof also being rounded and received in a tapered socket 62 with a rounded bottom, socket 62 being formed in one end portion of a piercing pin 63. The piercing pin is fashioned from round stock and has a slender portion 64 extending through central openings in the support platform and the main body base respectively, the piercing pin terminating in a puncturing point 65. The piercing pin also has an enlarged portion 66 in which the socket 62 is formed, the difference in the diameters of the portions 64 and 66 providing a shoulder 67.

The enlarged portion 66 of the piercing pin has an annular projecting flange 68 against which one end of a coiled compression spring 69 reacts, the other end thereof reacting against the support platform 44, the latter being slightly hollowed out to provide a circular seat 71 for the spring and an abutting surface against which the shoulder 67 may engage for limiting movement of the piercing pin.

The main body base 41 has a threaded recess 72 whereby the cartridge 39 may be secured thereto, the cartridge having a threaded stem 73 received in the recess. The cartridge contains a suitable fluid under pressure, for example CO₂, which is sealed therein by conventional means including a sealing disc 74, which disc is adapted to be punctured or pierced to release the fluid from the cartridge. The main body base is also provided with an annular channel 75 communicating with the threaded recess 72 and with a plurality of bores or conduits 76, the latter in turn communicating with the interior of the tubular housing 21, suitable O-ring seals 77 and 78 being employed to prevent the escape of the fluid past the main body and piercing pin respectively.

Turning now to Fig. 3, it will be noted that the post 47 projecting from the support platform 44 is shown with space therebetween and the retaining member 49, which is true as well of the other posts, this condition existing when the marker is in the operative or armed condition thereof. It is also to be noted that in this condition the compression spring is extended and has urged the

enlarged portion of the piercing pin away from engagement with the annular seat 71, that is, away from the position thereof in Fig. 2. In order to maintain the marker in the safe or unarmed condition illustrated in Fig. 2, there is provided a safety tube or sleeve 79 which fits inside well 28 of casing 12, the inner end of the sleeve being adapted to engage the retaining member 49 and press the same against ends of the posts 47, the sleeve being retained in such position by means of a retaining or safety pin or bar 81 passing through a pair of apertures in the sleeve and engaging the ends of a pair of elongated slots 82, there being a series of such slots formed in the casing for a purpose which will later be made clear. Externally of the casing, the retaining pin 15 may be provided with a ring 83 adapted to be grasped to exert a pull on the pin for withdrawal thereof, it being understood that the other end of the retaining pin may be provided with a retaining wire 84, or the like, which is removed prior to withdrawal of the pin.

20 From an inspection of Figs. 2 and 3, it should be apparent that in the unarmed condition of the marker, the main body 38 has been depressed to the point that the retaining member 49 secured thereto engages the ends of the posts 47, flange 52 of the retaining member in 25 turn pressing the hub member 53, which, through the medium of the thrust-transmitting element 61, has pressed enlarged portion 66 of the piercing pin until the shoulder 67 thereon engages with seat 71 on the support platform 44 and whereby spring 69 has been compressed.

30 Simultaneously with movement of the piercing pin 63 into position with respect to the support platform as shown in Fig. 2, main body 38 carries cartridge 39 and sealing disc 74 therein away from puncturing point 65 of the pin so that it is not pierced thereby. The extent of movement 35 of the main body and the parts supported thereby can be appreciated by the amount of space 85 appearing between the main body base 41 and the support platform 44 in Fig. 2. Hence, with the retaining pin 81 and safety sleeve 79 removed, spring 69 associated with piercing pin 63 forces 40 the enlarged portion 66 thereof from seat 71, thrust-transmitting element 61, in turn, moving the actuating assembly hub member 53 and the main body 38 to the condition of parts shown in Fig. 3, in which it will be noted that the main body base 41 is in engagement with the support platform 44. It is also to be noted that, although the relative 45 positions of the puncturing point 65 and the sealing disc 74, as shown in Fig. 2, remain unchanged in Fig. 3, the enlarged portion 66 of the piercing pin 63, however, is spaced from seat 71 in Fig. 3 and the piercing pin is 50 capable of longitudinal movement against the force of spring 69 for the purpose of puncturing the disc.

Movement of the piercing pin to puncture the sealing disc and release the fluid under pressure contained in the cartridge is accomplished by impact of the actuator assembly with the water. Such impact may occur as a result of the vanes striking water entering well 28, either through the adjacent end of casing 12 or through the elongated slots 82, such impact serving to move the vanes and associated hub member 53 longitudinally or diagonally. 60 In either case, the thrust transmitting element 61 will transmit movement of the hub member to the piercing pin 63 and drive the puncturing point 65 against the force of spring 69 into the sealing disc 74, thereby puncturing the same and releasing the fluid under pressure in the cartridge, after which the spring is adapted to withdraw the puncturing point away from the sealing disc. For provision against the contingency that point 65 might jam in the sealing disc, the point may be grooved or channeled for escape of the fluid, notwithstanding failure of withdrawal of the point.

Upon puncturing of the sealing disc, the gas or fluid under pressure flows therethrough and by way of the annular channel 75 and conduits or bores 76 into the tubular housing 21, around the cartridge, and through the connector 24 into the floatation bag 31. Initial inflation and

expansion of the floatation bag will cause ejection of the cap 34 and the collapsed portion of the bag, after which the bag becomes completely inflated.

Mounting the main body for movement in the casing, as hereinbefore described, also serves to prevent inadvertent operation when the marker is in the armed or operative condition, Fig. 3. Thus, should the marker be dropped and impacted upon a surface with its closed or cap end, the greater mass of the main body will move the enlarged portion of the piercing pin into engagement with seat 71 ahead of action of the actuator assembly to move the pin to puncture the sealing disc.

In the use and operation of the marker device, it is secured to a length of leader cable, midway thereof, swirl connectors on the cable connecting it to the aircraft tow line and tow target, the closed or cap end of the marker being directed toward the target. Removed in turn are the retaining wire 84, the retaining or safety pin 81, the safety sleeve 79, and cover 35. The tow target 80, Fig. 1, is dropped from the flying aircraft and streams out at the end of the tow line and leader cable.

After target practice has been completed, the tow line is released or cut allowing the tow target and the marker attached thereto to fall to the water. Normally, during the fall to the water the tow target acts as a parachute for the marker and the marker enters the water first, impact with the water actuating the vanes and actuator assembly which forces the puncturing point 65 of the piercing pin into the sealing disc 74. The fluid or gas released from the cartridge passes to the floatation bag, as hereinbefore described, which bag begins to inflate and pressure exerted by inflation thereof forces cap 34 from the end of the marker casing, the bag also being forced out after which it inflates completely. A maximum of 60 seconds from the time of water entry is all that is necessary for complete inflation of the bag into an elongated object, orange-yellow in color, riding vertically in the water and visible under usual conditions for at least a thousand yards to observers on surface craft, the bag remaining inflated and afloat a half an hour or more, to mark the side of the fallen target.

From the foregoing description it will be apparent that there has been provided a marker for aerial tow targets which is compact and operates upon impact to eject and inflate an object which floats, is of a distinctive color and sufficient size for positively indicating the site of a fallen tow target for a considerable length of time and is readily identifiable by an observer at a considerable distance from the site.

Various modifications are contemplated and may obviously be resorted to by those skilled in the art without departing from the spirit and scope of the invention, as only a preferred embodiment thereof has been disclosed.

What is claimed and desired to be secured by Letters Patent of the United States is:

1. The combination of a marker with an aerial tow target adapted to be releasably attached to an aircraft and towed through the air thereby over a body of water, said marker comprising a casing connected to said target, a housing arranged within said casing and fixed intermediate thereto the ends thereof, a container disposed within said housing and in communication therewith, said container having fluid under pressure sealed therein by means including a breakable seal, movable means mounted within said casing and adapted to be moved for breaking said seal and releasing the fluid under pressure in said container, actuating means arranged within one end of the casing and responsive to impact for moving said movable means and breaking said seal, said actuating means being adapted to be operated in response to the force of impact received thereby as the marker falls into the water after the target and marker have been detached from the aircraft, and a normally collapsed inflatable element arranged within the other end of the casing and sealed to said housing in communication therewith, said

element being adapted to be inflated by said fluid as said seal is broken, said element when inflated having a portion thereof disposed above the water for providing a visual signal marking the site of the fallen target.

2. A marker as defined in claim 1, said movable means including a piercing pin, and said actuating means including a movable hub member and a thrust transmitting element interconnecting the member and said pin.

3. A marker as defined in claim 2, said hub member being mounted for substantially universal movement.

4. A marker as defined in claim 1, said movable means including an axially movable piercing pin having a socket formed in one end thereof, said actuating means including a hub member mounted for substantially universal movement, said hub member having a socket formed therein in facing relation to said first-named socket, and a thrust transmitting rod with its respective ends received in said sockets.

5. A marker as defined in claim 4, each of said sockets having tapered walls and a rounded bottom, and said ends of the rod being rounded.

6. In a marker of the class disclosed, in combination, a casing, a support within said casing and fixed thereto, a body within said casing mounted for movement relative thereto, a cartridge containing fluid under pressure secured to said body and movable therewith, elongated means mounted for axial movement in said body and adapted to release said fluid after a predetermined amount of movement relative to the cartridge and body, said elongated means having an enlarged portion for engagement with said support, resilient biasing means connected to said elongated means and said support for biasing said enlarged portion away from engagement with the latter, said resilient means normally maintaining said enlarged portion spaced from engagement with said support in the operative condition of the marker, actuating means operatively connected to said body and said elongated means for moving the latter against the bias of the biasing means to release said fluid, and safety means engageable with said body for moving the same and simultaneously therewith move said actuating means and elongated means until said enlarged portion is in engagement with said support, the cartridge moving with said body in the same direction as said elongated means whereby release of the fluid thereby is precluded.

7. In a marker as recited in claim 6, said body including a circular base, walls projecting in one direction from said base and defining a cup-like cavity therebetween, said body being formed with circumferentially spaced slots in said walls and co-extensive therewith, said support having legs fixed to said casing with a leg disposed in each of said slots respectively, said actuating means including a hub member disposed in said cup-like cavity, said enlarged portion of said elongated means being disposed between said hub member and support, and retaining means secured to said walls and engageable with said hub member for retaining the same in said cup-like cavity.

8. In a marker as recited in claim 7, said retaining means bridging said slots, and each said leg carrying resilient means reacting thereagainst and said retaining means for urging said base into engagement with said support.

9. In a marker as recited in claim 7, said actuating means being operatively connected to said elongated means by means including a thrust-transmitting element between said hub member and said enlarged portion, said hub member and enlarged portion being formed with sockets receiving opposite ends of said element.

10. The combination of a marker with an aerial tow target adapted to be releasably attached to an aircraft for towing thereby through the air over water, said marker comprising an elongated casing having a pair of wells formed in the opposite ends thereof respectively, a housing disposed in said casing between said wells, a body disposed in one of said wells and sealed to said housing

at one end thereof, a cartridge secured to said body and disposed within said housing, conduit means in said body in communication with said cartridge and the interior of said housing, said cartridge containing gas under pressure sealed therein by means including a puncturable disc, a puncturing pin mounted for axial movement in said body, an impact responsive actuator disposed in said one well and mounted on said body for substantially universal movement, said actuator having vanes thereon and said one well having slotted walls for admitting water to said vanes, a free floating element between said actuator and pin and in engagement therewith, said element being movable by said actuator for moving said pin axially and puncturing said disc, a normally collapsed inflatable floatation bag arranged within said other well, said bag having a mouth portion secured to the other end of said housing and in communication with the interior thereof, and means closing said other well for protecting said bag,

initial inflation of said bag forcing said last-named means from said other well, complete inflation of said bag providing a position indicator.

5 11. A marker as recited in claim 10, and detachable safety means including a sleeve arranged within said one well in engagement with said body for preventing movement of said pin, and retaining means including a rod extending through said sleeve and slotted end of the casing.
